(57) **CLAIM**

The ornamental design for a punnet, substantially as shown and described.

DESCRIPTION

FIG. 1 is a top view of a punnet showing our new design; FIG. 2 is a front view thereof;

FIG. 3 is a rear view thereof;

FIG. 4 is a left side view thereof;

FIG. 5 is a right side view thereof;

FIG. 6 is top perspective view thereof; and,

FIG. 7 is a plan view of the punnet showing the punnet in a blank configuration.

The broken lines depict perforations and form part of the claimed design.
